EXTRACTOR COVER

Ella Barbour, Los Angeles, Calif.

Application March 4, 1932, Serial No. 596,792

12 Claims. (Cl. 210—63)

This invention relates to and has for an object the provision of an improved type of extractor cover formed of flexible material, of circular shape, reinforced at its outer edge and its central portion so as to provide ample rigidity and strength for supporting the cover in operative position during the rapid rotation of the extractor, and yet sufficiently flexible so as to render the cover more readily attachable and detachable.

10 A particular object of the invention is to provide a circular cover with a central opening therein and a radial slit extending from said opening to the outer edge with overlapping flaps, together with means for reinforcing the cover so that the necessity for buckles or other fastenings at the flaps is eliminated.

Other objects will appear as the description progresses.

In the accompanying drawings I have shown a preferred form of extractor cover embodying my improvements, in which

Fig. 1 is a top plan view.

Fig. 2 is a fragmentary sectional elevation of an extractor such as is used in laundries with my improved cover in operative position thereon.

Fig. 3 is a fragmentary composite sectional plan of the central portion of the cover.

Fig. 4 is a fragmentary sectional plan of the same showing details of the structure.

30 Figs. 5, 6 and 7 are, respectively, cross sectional views of the cover as shown in Fig. 1 on lines 5—5, 6—6 and 7—7.

The body of the cover is preferably formed of two overlapping circular sheets of fabric 1 and 2 with a peripheral reinforcing strip 3 bent inwardly at 4 and 5 over and extending entirely around the sheets 1 and 2 and stitched thereto at points 6, 6 etc. (See Figs. 1 and 7).

40 The body members 1 and 2 are cut on radial lines 7 and 8 from the axis thereof and said lines diverge as shown in Fig. 1.

Flaps 9 and 10 are sewed to the radial edges of the sheets 1 and 2 at points 11 and 12. Each of

45 said flaps comprise two thicknesses 13 and 14 of substantially heavy fabric such as canvas, which overlap the radial edges of the sheets 1 and 2, as shown in Fig. 5, and said thicknesses are additionally stitched together at points 15 near their outer edges. Thus the flap 10 substantially over-

50 laps the flap 9 when the cover is operatively positioned on the extractor.

A central opening 16 is provided in the cover around which the cover is reinforced so as to withstand the strains of constant use at high rotative speeds. The opening 16 is for the purpose of re-

ceiving the vertical shaft 17 of an extractor 18, which has a rotatable receptacle 19 housed within the extractor 18 and provided with a detachable annular metallic ring 20. The cover is reinforced around the opening 16 by means of a plurality of stranded cords, preferably arranged in pairs, as shown in Fig. 6. I have found that usually four cords formed of stranded cotton of approximately $\frac{1}{4}$ " in diameter are sufficient to properly reinforce the cover. Accordingly I have shown in Fig. 6 a pair of such cords 21 and 22 disposed on one side of the cover, and another pair of similar cords 23 and 24 oppositely positioned on the other side of the cover. Each of said pairs of cords are preferably separately wrapped and attached to the body of the cover.

To this end I provide two separate but similar sheets of material 25 and 26 which overlap the outer surfaces of the body members 1 and 2, and as shown in Fig. 3, are cut into stellate form so as to provide a plurality of triangular or pointed portions 27, 27 in the spaces corresponding to the opening 16.

Each pair of cords is positioned one within the other in circular form over the opening 16 and the pointed portions 27 are then bent inwardly around the pairs of cords and thence downwardly over the sheets 25 and 26 on which the portions 27 are formed. When the cords 21, 22, 23 and 24 are thus positioned around the opening 16 on the cover a plurality of straps, as at 28, 28 etc. of the same material of which the cover is made are extended radially around the cords overlying the portions 27 so that their ends 29 and 30 will overlap each other and the two overlapped ends of each of the members 28 will also overlap the reinforcing sheets 25 and 26, as shown in Fig. 6.

It will be noted that the members 28 are overlapped substantially at their edges, as shown in Figs. 1 and 3, so that the corded opening 16 of the cover is reinforced with a plurality of thicknesses at all points around the shaft 17.

After the wrappings just described have been properly positioned a pair of annular reinforcing members 31 and 32 of similar form and size are positioned on opposite sides of the several thicknesses of materials and all of the several thicknesses are stitched together permanently at points 33, 34, 35, 36 and 37.

It will be observed by reference to Fig. 4 that the ends 38 of all of the cords 21, 22, 23 and 24 are fringed and turned outwardly from the opening 16 for a distance of several inches so that when the several thicknesses of material are

stitched together with the cords in proper position the fringed portions will be also stitched to the fabric and will thus prevent the movement of the cords on the cover.

5 The formation of the cover as shown and described herein renders reinforcement by leather or material other than canvas of which the cover is made unnecessary, thereby reducing weight and unnecessary stiffness.

10 It will be understood that in a cover of this character for use on an extractor, the receptacle of which rotates at a very high speed, it is necessary to provide a cover formed of fabric so that the articles of clothing within the receptacle 19
15 will not be chafed, abraded or torn by contact therewith. Therefore, it is necessary to provide a substantially flexible cover having sufficient rigidity at its outer and inner edges to withstand the strains of centrifugal force set up by the high
20 rotative speed of the extractor.

25 A cover constructed in accordance with my improvements with the flaps 9 and 10 substantially overlapped obviates the necessity for attaching the ends of the cover together, as in other types
30 of flexible covers, for the reason that when the cover, as seen in Fig. 1 with the flap 10 overlying the flap 9, is rotated in a counter-clockwise direction the flap 10 would not tend to be displaced from its position relative to flap 9. As a matter of fact the rotation of the cover as stated would tend to draw the flaps 9 and 10 into more perfectly overlapped positions.

35 The provision of a plurality of flexible cords 21, 22, 23 and 24 wrapped and attached to the cover as shown and described provides ample rigidity at the center of the cover around shaft 17 and yet sufficient flexibility to permit the ready attachment of the cover to and its removal from an extractor.

40 Other advantages of my cover will appear to those familiar with the use and operation of extractors of the character shown and described.

What I claim is:

45 1. An extractor cover comprising a body formed of a flexible fabric with a central opening therein, said body provided around said opening with a plurality of portions cut on radial lines from the axis of the cover, a plurality of flexible cords overlying said body and formed in a circle around said opening, said cut portions bent around said cords at the margin of said opening and thence downwardly into positions overlying said body, and annular reinforcing sheets of fabric concentric with the cover overlying and stitched to the cut portions and the body.

50 2. An extractor cover comprising a body formed of a flexible fabric with a central opening therein, said body provided around said opening with a plurality of portions cut on radial lines from the axis of the cover, a plurality of flexible cords overlying said body and formed in a circle around said opening, said cut portions bent around said cords at the margin of said opening and thence downwardly into positions overlying said body, and annular reinforcing sheets of fabric concentric with the cover overlying and stitched to the cut portions and the body, said cover cut on radial lines from said opening to its outer edge, and overlapping flaps
55 attached to said radial edges for closing the opening thus formed.

60 3. An extractor cover comprising a body formed of a flexible fabric with a central opening therein, said body provided around said opening with a plurality of portions cut on radial lines from

the axis of the cover, a plurality of flexible cords overlying said body and formed in a circle around said opening, said cut portions bent around said cords at the margin of said opening and thence downwardly into positions overlying said body, and annular reinforcing sheets of fabric concentric with the cover overlying and stitched to the cut portions and the body, said cover cut on radial lines from said opening to its outer edge and overlapping flaps attached to said radial edges for closing the opening thus formed, the ends of said cords being fringed and bent outwardly between the body and said reinforcing sheets of material for securing the cords against movement.

65 4. An extractor cover comprising a body formed of a circular sheet of fabric with a central opening therein, a plurality of strips of material arranged with their edges substantially overlapped and forming loops around said opening and their end portions overlying opposite sides of the body, a plurality of flexible cords enclosed within the loops of said strips and having their ends fringed and bent outwardly over the body, and annular reinforcing sheets of material overlapping the ends of said strips on opposite sides of and permanently attached to said body.

70 5. An extractor cover comprising a body formed of a circular sheet of fabric with a central opening therein, a plurality of strips of material arranged with their edges substantially overlapped and forming loops around said opening and their end portions overlying opposite sides of the body, a plurality of flexible cords enclosed within the loops of said strips and having their ends fringed and bent outwardly over the body, and annular reinforcing sheets of material overlapping the ends of said strips on opposite sides of and permanently attached to said body, said body and said reinforcing members being cut to form a radial opening extending from said central opening to the outer edge of the cover, and overlapping flaps secured to the edges of said radial opening but detached from each other while the cover is in use.

75 6. An extractor cover comprising a body formed of a circular sheet of fabric cut on radial lines at a plurality of points from the axis to provide a plurality of cord attaching portions, said portions being bent outwardly so as to form loops at corresponding distances from the axis and thence downwardly over the body, a plurality of flexible cords extending thru said loops, a pair of flexible reinforcing members overlying said cut portions and the opposite sides of said body and stitched thereto, said loops being extended around a central opening in the cover and said cords reinforcing the cover around said opening.

80 7. An extractor cover comprising a body formed of a circular sheet of fabric cut on radial lines at a plurality of points from the axis to provide a plurality of cord attaching portions, said portions being bent outwardly so as to form loops at corresponding distances from the axis and thence downwardly over the body, a plurality of flexible cords extending thru said loops, a pair of flexible reinforcing members overlying said cut portions and the opposite sides of said body and stitched thereto, said loops being extended around a central opening in the cover and said cords reinforcing the cover around said opening, the ends of said cords being fringed and bent outwardly between said cover and said reinforcing members, for the purpose described.

85 8. An extractor cover comprising a body formed

- of a circular sheet of fabric cut on radial lines at a plurality of points from the axis to provide a plurality of cord attaching portions, said portions being bent outwardly so as to form loops 5 over the body, a plurality of flexible cords extending thru said loops, a pair of flexible reinforcing members overlying said cut portions and the opposite sides of said body and stitched thereto, said loops being extended around a central 10 opening in the cover and said cords reinforcing the cover around said opening, and an outer wrapping around said opening comprising a plurality of strips of fabric with their edges overlapped around said loops and their ends overlying opposite sides 15 of said cover and secured in position between said cover and said reinforcing members.
9. An extractor cover comprising a circular sheet of fabric having a radial opening and an axial opening therein, a plurality of reinforcing 20 cords extending around said opening adjacent said cover with their ends secured to the cover adjacent said radial opening, the inner portion of said cover being provided with a plurality of radially disposed portions forming loops for the 25 reception of said cords and having their ends permanently attached to the cover around said opening.
10. An extractor cover comprising a body 30 formed of a circular sheet of fabric having a central opening therein and a radial opening leading from said central opening to the outer edge of the cover, a stellate member around said opening and overlying said body, a plurality of flexible cords extending around said central opening on said cover within said stellate member, the central portion of said cover and said annular 35 member being bent to form loops around said opening for enclosing said cords and thence outwardly over and attached to the cover for retaining the cords in position around said opening, and an outer wrapping for said loops also attached to the cover at its outer margin.
11. An extractor cover comprising a body 40 formed of a circular sheet of fabric having a central opening therein and a radial opening leading from said central opening to the outer edge of the cover, a stellate member around said opening and overlying said body, a plurality of flexible cords extending around said central opening on said cover within said stellate member, the central portion of said cover and said annular member being bent to form loops around said opening for enclosing said cords and thence outwardly over and attached to the cover for retaining the cords in position around said opening, 45 80 85 90
12. An extractor cover comprising a body 50 formed of a circular sheet of fabric having a central opening therein and a radial opening leading from said central opening to the outer edge of the cover, a stellate member around said opening and overlying said body, a plurality of flexible cords extending around said central opening on said cover within said stellate member, the central portion of said cover and said annular member being bent to form loops around said opening for enclosing said cords and thence outwardly over and attached to the cover for retaining the cords in position around said opening, and a pair of reinforcing sheets of material overlapping the central portion of and attached to said cover around said opening. 55 100 105 110
